RAZOR STROPPING DEVICE

Washington I. Tyndall and William E. Underwood, Wilson, N. C.

Application July 29, 1935, Serial No. 33,790

2 Claims. (Cl. 51—115)

This invention relates to apparatus for stropping straight or hollow ground razors such as barbers use.

An object of the invention is to provide novel stropping members which are annular in form and mounted eccentrically on revoluble disks to more effectively strop the razor than hitherto possible.

A further object is to provide novel means for regulating the pressure of the razor blade against the stropping members so that at the beginning of the stropping operation the blade will be pressed lightly against the stropping members alternately, the pressure gradually increasing as the stropping operation continues, and then gradually decreasing to nearly zero at the end of the stropping operation whereby a true edge is produced during the stropping operation in contrast to the deformed or slightly turned over edge usually to be found where constant high pressure is used.

A further object is to provide novel means for locking the blade holder in a central position between the stropping disks at the end of the stropping operation so that the blade can be removed without damage to the leather stropping members or to the blade and a new blade inserted without damage to the blade or stropping members.

A further object is to provide novel means for controlling the stropping operation to continue through a predetermined time period so that when a single operating lever is pressed the motor controlling switch will be manually closed and thereafter said mechanism will continue to operate through the predetermined time period and then automatically open the switch to de-energize the motor.

A further object is to provide a novel blade holder for supporting the blade at the back and on both sides so that both the back and the edge of the blade may bear against the stropping member simultaneously as is the case when hand stropping a razor.

A further object is to provide novel means for oscillating the blade holder to apply the blade to the stropping members alternately without shock or jar.

A further object is to provide a device of this character which will be inexpensive to manufacture, and which will not easily get out of order.

With the above and other objects in view the invention consists of certain novel details of construction and combinations of parts here-

inafter fully described and claimed, it being understood that various modifications may be resorted to within the scope of the appended claims without departing from the spirit or sacrificing any of the advantages of the invention.

In the accompanying drawings forming part of this specification:

Figure 1 is a front elevation of a razor stropping machine constructed in accordance with the invention.

Figure 2 is a side elevation of the parts shown in Figure 1.

Figure 3 is a front elevation with parts in section and parts removed to expose the blade holder oscillating mechanism.

Figure 4 is a cross sectional view taken on the line 4—4 of Figure 1.

Figure 5 is a detail cross sectional view taken on the line 5—5 of Figure 4.

Figure 6 is a detail perspective view of one part of the blade holder.

Figure 7 is a detail front elevation showing certain of the parts in larger scale than in Figure 1.

Figure 8 is a side elevation showing the eccentrically mounted stropping disks.

Figure 9 is a cross sectional view taken on the line 9—9 of Figure 7.

Referring now to the drawings in which like characters of reference designate similar parts in the various views, 10 designates a base plate which is equipped at the sides with standards 11 having bearings 12 to receive the ends of a revoluble shaft 13. The shaft is preferably driven by an electric motor 14 which is operatively connected to the shaft by a belt drive 15.

A pair of disks 16, which may be formed of sheet metal or other light strong material, is fixed eccentrically on the shaft near one end thereof, preferably each disk having a flanged hub 17 which is secured to the disk by screws 18 or similar connectors and is secured to the shaft by a set screw 19 or similar connector. The opposed faces of the disks are equipped with annular stropping members 20, formed of leather or other suitable material and secured eccentrically to the disk in any preferred manner.

The razor blade holder comprises an oscillatory shaft 21 the ends of which are journaled in bearings 22 on the upper ends of a standard 23 and a plate 37 on the base plate. The shaft extends at a right angle to the drive shaft 13, and is provided with an integral plate 24 which is substantially oblong and is provided in the longitudinal edge with a depression or groove 25 which is

arcuate in contour to receive and to conform to the contour of the back 26 of a razor blade 27 of the straight or hollow ground type used by barbers.

5 A pair of clamps 28, one of which is shown in
Figure 6, is secured to the side faces of the plate
24 and extend along the sides of the blade and
yieldably engage the blade. The clamps contact
with the curved wall of the groove 25 in the plate
10 to hold the blade in proper position between the
stropping disks so that the back and the edge of
the blade will be held against the stropping mem-
bers just as is done when hand stropping a razor.
Each clamp member 28 comprises a resilient bar
15 having a leg 29 at one end which may be riveted
or otherwise rigidly secured to the plate 24 and
having at the opposite end a substantially tri-
angular web 30 provided at the bottom with a tab
20 31 which may be riveted or otherwise rigidly se-
cured to the plate 24. The contour of the inner
edge of each web is substantially a duplicate of
the contour of the corresponding side and back
of the razor and permits the razor blade being
easily guided longitudinally between the clamp
25 bars 29.

The razor blade is oscillated by the shaft 21 and is engaged with the annular eccentric stropping members alternately. For this purpose the shaft 21 is provided with an integral crank 22 which is provided with a pin 33 having a roller 34 thereon. As best shown in Figure 3, a pair of L shaped rocker arms 35 are pivoted, as shown at 36, near their elbows on a plate 37 which rises from the front edge of the base plate. Each rocker arm is equipped with a facing 38 of yielding material to engage the roller 34 and to eliminate shock, jars and noise. The rocker arms are equipped with vertically disposed helical springs 39 which are secured at the upper ends to adjusting screws 40 carried by horizontal bracket arms 41 which will be hereinafter more fully described. The springs tend constantly to swing the rocker arms and the crank 32 of the blade holder.

45 The rocker arms are alternately withdrawn from engagement with the crank 32 so that the springs 39 impart oscillating movement to the shaft 21 and for this purpose a worm pinion 42 is fixed to the drive shaft 13 and meshes with 50 a worm gear 43 on a shaft 44, journaled in a tubular bearing 45 carried by a bracket 46 on the base plate 10. A gear 47 on the shaft 44 has a crank 48 to which one end a pitman 49 is connected, the opposite end of the pitman being connected to a shift link 50 which is pivoted at the 55 lower end, as shown at 51, to the plate 37 between the rocker arms. The shift link is equipped at the upper end with a pin 51 having a roller 52 thereon to engage with the rocker arms alternately and remove each arm in turn from engagement with the crank 32 to permit the spring 60 39 of the mating arm to rock the blade holder.

It is desirable that the tension of the spring be controlled so that the razor blade will be pressed gently against the stropping members at the beginning of the stropping operation and that this condition be repeated at the end of the stropping operation so that at the beginning the blade will not be thrown with a slap against either stropping member and at the end the blade will be stropped without pressure so that there will be no danger of turning the edge of the blade as would be the case with a maximum pressure exerted on the blade through the entire stropping operation. For this purpose the above

mentioned bracket arms 41 are fixed to a U shaped frame comprising rods 53 which are connected together at the bottom by a cross bar 54 and are slidably fitted in tubular guides 55 carried by the plate 37.

The cross bar 54 is provided centrally with an upstanding lug 56. A connecting link 57 is pivoted at the lower end to the lug, as shown at 58, and at the upper end is pivotally connected to one end of a long lever 59 which is fulcrumed, as shown at 60, on an arm 61 which projects from the plate 37. The link 57 is provided with a slot 62 to receive a pivot pin 63 which connects the lever to the link. The end of the lever 59 projects beyond the side of the machine so as to be easily rocked downwardly by pressure of the operator's hand to raise the inner end of the lever and move the U shaped frame vertically from the position shown in Figure 1 to extend the springs and place them under tension, as shown in Figure 7. 10 15 20

As later described the control switch of the motor is automatically closed as soon as the operator starts to push the lever 59 downward so that the holder and blade begins to oscillate before the tension of the springs has reached maximum. Thus the blade is pressed gently against the stropping members at the beginning of the stropping operation, the pressure gradually increasing to maximum as the springs are tensioned to maximum extent during the final stages of downward movement of the lever 59 by the operator. For decreasing the pressure of the springs gradually during the final stages of the stropping operation a slow motion transmitting mechanism is employed.

The slow motion mechanism comprises a gear train designated in general by the numeral 64, the initial gear of which is driven by the gear 47 which carries the pitman 49. The final gear 40 of the gear train carries a pivoted spring pressed dog 65 which engages a ratchet gear 66 loosely mounted on the shaft 67 of the final gear of the gear train. A link 68 is swivelly mounted on the shaft 67, and is fixed integrally to the ratchet gear 66. The link is provided at the outer end with a pin 69 which rides in an L shaped slot having a horizontal leg 70 and a vertical leg 71, the slot being formed at the outer end of the lever 69 in such manner that the pin 69 rides up in the vertical leg 71 of the slot and outwardly in the horizontal leg 70 of the slot when the lever is manually depressed from the full line position shown in Figure 1, to the dotted line position. A vertically disposed spring 72 is connected to the lever 59 between the fulcrum thereof and the U shaped frame and tends constantly to pull down the inner end and lift the outer end of the lever. 50 55

During downward movement of the outer end of the lever 59 under pressure of the operator's hand the link 68 will carry the ratchet gear 66 and at the limit of the downward movement of the lever the dog 65 locks the ratchet gear to the final gear of the slow motion gear train. The motor having automatically started during the initial downward movement of the outer end of the lever 59, the gear train will now permit the link 68 to swing up slowly. During upward movement of the link 68 the pin 69 rides inwardly in the horizontal leg 70 of the L shaped slot. As the outer end of the lever rises the inner end is slowly pulled down by the spring 72 and moves the U shaped frame downwardly to gradually relieve the springs 39 of tension.

This gradual release of tension of the springs 39 accomplishes a gradual decrease of pressure of the blade upon the stropping members as the stropping operation progresses. Finally the pin 5 61 reaches the inner end of the horizontal leg 70 of the slot and drops sharply to the bottom of the vertical leg 71 of the slot to relieve the spring 39 of all tension and to simultaneously cut off the actuating motor as will now be described.

By referring to Figure 1 it will be seen that a stationary switch contact 73 is mounted on the base 10. A movable switch contact 74 is pivoted, as shown at 15, on an arm 76 rising from the base and is spring pressed by a helical spring 77 into engagement with the fixed switch contact 73. A hook 78 is connected to the pivoted switch contact and has the upper end engaged over the upper edge of the lever 59. When the 20 outer end of the lever 59 is pressed downwardly by the operator the spring 77 closes the switch during the early stages of downward movement of the lever so that the razor blade is oscillated before maximum tension has been placed upon 25 the springs 39. During final stages of downward movement of the outer end of the lever the hook 78 leaves the lever, as shown by dotted line but remains in the path of return movement of the lever so that at the movement the 30 pin 69 drops into the vertical leg 71 of the L shaped slot in the lever the hook will be engaged with the lever to raise the movable switch contact and open the switch to de-energize the motor.

It is desirable that the blade holder 24 be brought to rest midway between the stropping disks at the end of the stropping operation so that the razor blade may be removed and another blade inserted without damage to the 35 stropping members or blade. For this purpose the crank arm 32 of the blade holder is equipped with a pin 79 as best shown in Figure 4. The pin projects through an arcuate slot 80 formed in the plate 37 below the bearing 22 of the oscillating shaft 21. The slot is concentric with the shaft so that as the shaft oscillates the pin will move laterally to the ends of the slot. A locking plate 81 is slidably mounted between vertical guides 82 disposed on the plate 37 and 40 is provided in the top edge with a notch 83, which is adapted to receive the pin 79 when the latter is in central position with respect to both stropping disks 16 and lock the blade holder in position midway between the stropping 45 members.

The locking plate 81 is lowered to release the pin 79 just prior to closing of the switch to start the motor, and for this purpose a lever 84 is pivoted on a lug 85 on the plate 37, as 50 shown in Figure 9, one end of the link being bifurcated, as shown at 86, to receive a pin 87 which projects from the locking plate 81. The opposite end of the lever is provided with a lip 88 which projects into the path of movement 55 of a lug 89 formed on the bottom edge of the lever 59, as best shown in Figure 7. A helical spring 90 is terminally connected to the plate 37 and to the outer end of the link 84 and tends constantly to hold the link in position to hold the locking plate 81 withdrawn from the pin 79 and lodged against a stop pin 91 on the plate 37.

When the outer end of the lever 59 is manually depressed the inner end of the lever is raised 75 from the position shown in Figure 1 whereupon

the lug 89 lifts from engagement with the lip 88 and permits the spring 90 to rock the lever 84 and disengage the locking plate 88 from the pin 79, as shown in Figure 7. When the pin 69 drops to the bottom of the vertical leg 71 of the L shaped slot in the lever 59, the lug 89 impinges against the lip 88 and rocks the lever 84 to slide the plate 81 upwardly in the guides 82 so that the notch 83 intercepts the pin 79 and brings the blade holder to a stop midway between the 10 stropping disks.

It will be observed that the annular eccentric stropping members 20 have wiping contact with the edge and back of the blade, as best shown in Figure 5, and during a complete revolution 15 each stropping member progressively advances longitudinally of the blade. The timing of the oscillatory movement of the blade holder relatively to the rotating movement of the stropping members is such that whenever the blade is 20 shifted from one stropping member to the other the blade will engage the stropping member at a point approximately 90 degrees beyond the point where it initially engaged the stropping member on its preceding encounter therewith. 25 For example, during four engagements of the blade with a stropping member, the first contact of the stropping member may be near the heel of the blade, the next near the center of the razor blade, as shown in Figure 4, the next beyond the center, and the final at the toe of the blade. The advantage of this is that the keen edge of the blade is not damaged as is the usual case where the stropping member always makes 30 initial contact with the blade at the same point. 35

In operation the razor blade 27 is slid forwardly between the clamps 28 with the back of the razor bearing on the rounded surface 25 of the holder until the heel of the blade is disposed beyond the guides 30. The operator now 40 depresses the outer end of the lever which movement automatically closes the motor controlling switch 74, disengages the locking plate 81 from the pin 51 of the holder, and lifts the U shaped frame to place the springs 39 under tension. The 45 motor oscillates the blade holder, rotates the stropping disks, and moves the slow motion gear 34 to swing the link 68 upwardly slowly and permit the spring 72 to pull down the inner end of the lever 59 slowly to gradually decrease 50 the tension of the springs 39. Finally the pin 89 drops into the vertical leg 71 of the L shaped slot in the lever. Thereupon, the lever under 55 urge of the spring 72, opens the switch to shut off the motor, and depresses the lever 84 to engage the notch of the locking plate with the pin 79 of the blade holder so that the holder stops midway between the two stropping disks.

From the above description it is thought that the construction and operation of the invention 60 will be fully understood without further explanation.

What is claimed is:

1. A razor stropping device comprising a pair 65 of revoluble stropping members, an oscillating blade holder projecting between the members, means for automatically controlling oscillation of the blade holder to gradually decrease the pressure of the blade against the stropping members during the final stages of the stropping operation, and means for controlling the oscillation of the blade holder to gradually increase the pressure of the blade against the stropping members during the initial stages of the stropping operation. 70 75

2. A razor stropping device comprising a pair of revolute stropping members, a pivoted blade holder projecting between the members, oscillating means for rocking the blade holder, a manually operable spring pressed lever, a locking plate operatively connected to be moved by the lever, and a pin carried by the holder en-

gageable by the locking plate to lock the holder stationary in position midway between the stropping members at the end of the stropping operation.
